(57) **CLAIM**

I claim the ornamental design for a combined cell phone case and pill carrier, as shown.

DESCRIPTION

FIG. 1 is a perspective view of the combined cell phone case and pill carrier showing my new design;

FIG. 2 is a perspective view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a side elevation view thereof;

FIG. 8 is an opposite side elevation view thereof; and,

FIG. 9 is a perspective view of the combined cell phone case and pill carrier with a package of pills partially inserted into the carrier.

The broken line showing of environment in the drawings is included for the purpose of illustrating only and forms no part of the claimed design.
